[57] CLAIM

The ornamental design for an ottoman, as shown and described.

DESCRIPTION

FIG. 1 is a perspective view of an ottoman embodying my design;

FIG. 2 is a top plan view thereof on an enlarged scale;

FIG. 3 is an elevational view of the ottoman of FIG. 2 and showing one of the two identical sides;

FIG. 4 is an end elevational view of the ottoman of

FIG. 2, the opposite end being a mirror image thereof; and

FIG. 5 is a bottom plan view of the ottoman shown in

FIG. 2.
